UNITED STATES PATENT OFFICE.

CLARK P. WILDER, OF CHICAGO, ILLINOIS, ASSIGNOR TO WESTERN HORSE-SHOE PAD COMPANY, OF CHICAGO, ILLINOIS.

DESIGN FOR A HORSESHOE-PAD.

SPECIFICATION forming part of Design No. 35,262, dated November 5, 1901.

Application filed April 11, 1901. Serial No. 55,430. Term of patent 7 years.

To all whom it may concern:

Be it known that I, CLARK P. WILDER, a citizen of the United States, and a resident of Chicago, in the county of Cook and State of Illinois, have invented and produced a new and original Design for Horseshoe-Pads, of which the following is a specification, reference being had to the accompanying drawings, forming a part thereof.

Figure 1 is a perspective view of the bottom of a pad shaped according to my design. Fig. 2 is a plan view of the top of same. Fig. 3 is a side elevation.

The leading or material feature of my design consists in the horseshoe-pad formed of the thin flattened part 1, having the enlargement or cushion 3 on one face thereof and extending across the rear part of said face, said cushion having the two webs 4 extending forward of same, having its forward edge 8 extending in a straight line between said webs and having its forward face between and at

each side of said web sloping forward toward the plane of the flattened part 1, said flattened part being cut out forward of the slope 25 between said webs. The face of the cushion is roughened by the intersecting corrugations 5, and the front edge 8 of the cushion is straight. Between the webs 4 the front side 6 of the cushion has a gradual slope to the 30 edge of the opening 2. The remaining portions of the front side 7 have a gradual curved slope from the edge 8 of the cushion forward and meeting the pad 1.

What I claim as new, and desire to secure 35 by Letters Patent, is—

The design for a horseshoe-pad, substantially as herein shown and described.

Signed by me at Chicago this 9th day of April, 1901.

CLARK P. WILDER.
